(57) **CLAIM**

The ornamental design for a breast milk collector, as shown and described.

DESCRIPTION

FIG. 1 is a perspective view of a breast milk collector, illustrating my new design;

FIG. 2 is a front elevational view;

FIG. 3 is a rear elevational view;

FIG. 4 is a right-side elevational view;

FIG. 5 is a left-side elevational view;

FIG. 6 is a top plan view; and,

FIG. 7 is a bottom plan view.

The broken lines in the drawings depict portions of the breast milk collector that form no part of the claimed design.
